UNITED STATES PATENT OFFICE

93,112

DESIGN FOR AN OUTBOARD MOTOR

Harry L. Johnson, Waukegan, Ill., assignor to
Johnson Brothers Engineering Corporation,
Waukegan, Ill., a corporation of Indiana

Application April 9, 1934, Serial No. 51,352

Term of patent 7 years

To all whom it may concern:

Be it known that I, HARRY L. JOHNSON, a citizen of the United States, residing at Waukegan, in the county of Lake and State of Illinois, have invented a new, original, and ornamental Design for Outboard Motor, of which the following is a specification, reference being had to the accompanying drawing, forming part thereof.

In the drawing:

Fig. 1 is a side elevation of an outboard motor

having a power head in accordance with this invention.

Fig. 2 is a top plan view thereof.

Although an entire outboard motor is shown in Fig. 1 it is the power head thereof which is regarded as the dominant feature of the design.

I claim:

The ornamental design for an outboard motor as shown and described.

HARRY L. JOHNSON.
